(57) **CLAIM**

The ornamental design for a cutting board, as shown and described.

DESCRIPTION

FIG. 1 is a top, front right-side perspective view of embodiment one of a cutting board, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top view thereof;

FIG. 7 is a top, front, right-side perspective view of embodiment two of a cutting board, showing our new design;

FIG. 8 is a front elevation view thereof;

FIG. 9 is a rear elevation view thereof;

FIG. 10 is a left side elevation view thereof;

FIG. 11 is a right side elevation view thereof; and,

FIG. 12 is a top view thereof.

The portions of the cutting board shown in broken lines form no part of the claimed design. Bottom views of the embodiments of the cutting board are omitted because they are plain and unornamental and form no part of the claimed design.
